Primary Examiner — Natasha Vujcic(74) *Attorney, Agent, or Firm* — McAndrews, Held & Malloy, Ltd(57) **CLAIM**

We claim, the ornamental design for a ceiling-mounted air conditioner, as shown and described.

DESCRIPTION

FIG. 1 is a front perspective view of a ceiling-mounted air conditioner, showing our new design;

FIG. 2 is a front view thereof;

FIG. 3 is a rear view thereof;

FIG. 4 is a left-side view thereof;

FIG. 5 is a right-side view thereof;

FIG. 6 is a top view thereof;

FIG. 7 is a bottom view thereof;

FIG. 8 is an enlarged view of the portion 8 encircled in FIG. 1;

FIG. 9 is a cross-sectional view taken along the line 9-9 in FIG. 2; and,

FIG. 10 is an enlarged view of the portion 10 encircled in FIG. 9.

The dashed broken lines in the figures depict portions of the ceiling-mounted air conditioner that form no part of the claimed design. The dot-dot dash broken lines in the figures, encircling portions of the claimed design that are illustrated in an enlarged view, form no part of the claimed design.
